UNITED STATES PATENT OFFICE.

JOHN W. AYMAR, JR., OF NEW YORK, N. Y.

RUBBER HEEL.

Application filed September 27, 1921, Serial No. 503,604. Renewed February 28, 1923.

To all whom it may concern:

Be it known that I, JOHN W. AYMAR, Jr., a citizen of the United States, and resident of the borough of Manhattan, city, county, and State of New York, have invented certain new and useful Improvements in Rubber Heels, of which the following is a specification.

This invention relates to resilient heel lifts and in its generic aspect has for its object to provide an improved lift for shoe heels of rubber or other resilient material which is of such construction that certain material disadvantages existing in heel lifts of the constructions now in general use are entirely obviated.

It has heretofore been proposed to provide what is known as a concavo-convex rubber heel or lift in which the attaching and tread faces are double curve surfaces. In the application of such heel lifts to the leather heel of the shoe when the lift is flattened against the shoe heel it is impossible to bring all parts of the concave double curve attaching face of the lift into contact with the shoe heel. This is due to the fact that it is mathematically impossible to develop a double curved surface into a plane surface. Such impossibility of development of a double curve surface of the lift into the plane of the shoe heel when it is attached results in the formation of humps in the tread surface of the lift, due to the compressional stresses in all directions on the tread surface caused by flattening arches which exist in all radial planes normal to the double curved surface. This produces an uneven tread surface which causes uneven wear and gives the wearer the sensation of insecurity. Further, owing to the fact that all parts of the heel lift between the attaching nails are normally out of contact with the shoe heel, the heel lift when walked upon will tend to move alternately toward and away from the shoe heel, placing a heavy strain upon the attaching nails which causes them to become loosened and often results in the lift coming entirely off of the shoe heel. Also, due to the flattening out of the tread surface under the weight of the wearer and the loosening of the nails, the heel lift under pressure will creep laterally upon the leather shoe heel and protrude or extend beyond the marginal edge of the latter, thus producing an unsightly appearance.

Heels have been proposed and made embodying cylindrical surfaces in their attaching and tread faces, but in all such cases it has been found impossible to make the entire faces of the lift truly cylindrical, with the result that certain portions of lifts of this type between the cylindrical surface and the margin of the lift are composed of double curved surfaces which are blended with the cylindrical surface, so as to show no line of demarkation. The necessity of such construction in heels of the cylindrical type is due to the fact that within practical limits of rubber heel construction it is impossible to produce a heel embodying an unbroken cylindrical surface and having an outline or periphery conforming to the average shoe heel shape. It is obvious therefore that the development feature inherent in a cylindrical surface is lost to a heel having but a part of its attaching and tread surfaces cylindrical.

The above noted serious disadvantages existing in the practical application and use of the double curve and so-called cylindrical heel lifts of the concavo-convex type are entirely overcome by means of my present invention, and to this end I provide the heel lift with a completely developable attaching face comprising an unbroken conical surface.

It follows from the definition of a developable surface that a lift of this construction may be readily flattened against the leather shoe heel and every part of its attaching face brought into absolute contact with the leather heel. This is due to the fact that there are no arches in the direction of the elements of the surface of a cone to set up compressional stresses, when developed, in the tread surface and also to the fact that every two consecutive elements of a conical surface lie in a common plane. In the development of the attaching face of my heel into a plane surface, the desired tight hugging contact of the lift around its entire marginal edge and along the breast edge thereof, with the leather heel is produced. Thus I attain the essential object and purpose of the double curved type of heel lift with the complete elimination of its inherent disadvantages.

It is a further object of my invention to provide a heel lift as above characterized which, when attached, will be of absolutely uniform thickness throughout its structure,

all parts of the developed attaching and tread surfaces of the lift lying in parallel planes and providing an absolutely flat unbroken tread surface.

5 With the above and other objects in view the invention consists in the improved heel lift and in the several novel structural features thereof, as will be hereinafter more fully described, illustrated in the accompanying 10 drawing and subsequently incorporated in the subjoined claims. In the drawing wherein I have illustrated one desirable and practical embodiment of the invention;

15 Fig. 1. is a plan view illustrating a heel lift and showing diagrammatically the manner in which the geometrical formation of the attaching face of the lift is determined.

Fig. 2. is a vertical longitudinal sectional view through the lift.

20 Figure 3 is a vertical transverse sectional view taken on the line 3-3 of Figure 1, looking toward the rear of the heel.

25 Figure 4 is a sectional view on the line 4-4 of Fig. 1, looking in the direction of the arrows.

30 Figure 5 is a plan view illustrating in full and broken lines the comparative outline shapes of the heel lift before and after it is developed into a plane.

Figure 6 illustrates the improved lift attached to a shoe heel and showing that the lift has a perfectly flat tread surface.

35 Referring in detail to the drawing and more particularly to Figure 1 thereof I have shown the resilient lift having a curved outline or contour 10-11-12 corresponding to that of the average shape shoe heel, such as is common to the trade and which will hereinafter be referred to as the attaching 40 face edge. In the preferred embodiment illustrated this edge lies entirely in a plane. The breast edge of the lift is preferably a non-plane curve which extends between the 45 breast corners 10 and 12 of the lift. The central longitudinal section of the lift is a straight line 11-20, placed at a suitable angle with respect to the plane of the attaching edge and the inclination of this line 50 determines the depth of the breast edge at its center point 20, which is the point of the attaching face most remote from the plane of the attaching edge. The point 15 is in line with the central longitudinal section 55 of the lift 11-20 and constitutes a vertex or converging point for the rectilinear elements of the desired surface.

60 This line 11-15 is used as a rectilinear generatrix of the attaching face of the lift, by moving it so that it is in constant contact with the attaching face edge 10-11-12 used as a directrix and always passes through the vertex 15. The generation of this attaching surface may be more particularly described 65 by considering that 11-15 is the initial posi-

tion of the generatrix and that it creates one-half of the surface by moving along the attaching face edge 10-11 and always convergent to the point 15 as shown by the broken lines such as 16-17, in Fig. 1 of the 70 drawing. These lines represent typical positions of the generatrix during its progress from the point 11 to the point 10 on the attaching face edge of the lift. As the surface is symmetrical with respect to the center line 11-20, the other half of the surface may be similarly generated by moving the generatrix along the remaining portion of the attaching face edge between the points 75 11 and 12. It is obvious that the surface thus generated is conical in the general and broad sense of the term. This surface is terminated by the breast line 10-12 which corresponds to the line of the inter-section 80 of the conical surface with a vertically disposed cylindrical surface touching the breast corners 10 and 12.

85 It will be apparent to one familiar with the methods of generating mathematically exact surfaces that there are other ways of expressing the geometrical construction of the improved heel lift, depending upon the assumed conditions. The foregoing description therefore is in no sense intended as a 90 limitation upon the scope of the present invention, being here given merely as a preferred manner of clearly disclosing how the 95 present invention may be produced.

99 As shown in Figure 3 of the drawing a transverse section through the lift taken in a plane perpendicular to the attaching face edge on the line 3-3 of Fig. 1 will be a smooth curve. It follows from the fact that the attaching surface is conical that all other 100 parallel transverse sections will be of similar form. This is indicated by the dotted lines 3'-3' in Figures 1 and 3 of the drawings, 105 said lines indicating the curvature of the attaching face in a transverse section cut by a perpendicular plane parallel to the section 3-3. These various transverse curvatures of the attaching surface continually decrease in 110 depth from the breast to the rear end 11 of the lift.

115 Since conical surfaces of all varieties belong to a class known as developable surfaces, or in other words, surfaces which may flatten out or develop into a plane; it is obvious that the heel lift of my present invention has the inherent property of development so that the attaching surface is converted from a conical surface to a perfectly flat or plane surface when the lift is attached to the shoe heel by nails or other suitable attaching means such as are common in the 120 trade. This feature gives to the present improved heel lift a distinct advantage over other types of heel lifts having double curved surfaces, which are not capable of 125 development. It will be seen that when my 120

improved heel is attached the flattening of the transverse arcs will produce considerable pressure at both sides of the attaching face edge, such pressure being greatest at the 5 breast corners or at the ends of the arc of greatest depth. This is a desirable feature since the breast corners of the lift are subject to the greatest tendency to separate from the face of the leather heel in actual use.

10 Referring to Figure 4 of the drawings which represents a section in a vertical plane taken on the line 4—4 of Figure 1, it will be observed that an arch of considerable depth exists between the rear end 11 of the attaching face edge and the breast corner 10. A 15 like arch also exists in a similar vertical section extending from the point 11 to the other breast corner 12. The effect incident to flattening these two arches is to bring considerable 20 pressure at the rear of the attaching face edge so that it likewise will be held in close hugging contact against the leather face of the heel. The central longitudinal section through the lift extending in a 25 straight line would not create pressure at the central point 20 along the breast edge against the heel face, but it will be noted that all sections radiating from this point 20 to the attaching face edge of the lift are arches. 30 The combined effect of breaking down these arches when the lift is flattened against the heel will result in producing the necessary pressure of the entire breast edge of the lift against the heel face to provide a satisfactory 35 contact. In other words as any section extending from the breast edge to the attaching face edge except in planes intersecting the vertex 15 of the cone is an arch, the resultant effect of flattening out these arches produces pressure all along the breast line of the lift. It is thus apparent that the improved lift embodies a completely developable attaching surface which will give the desired close hugging contact against the 45 shoe heel face around the entire marginal edge of the lift.

In the foregoing description, I have referred mainly to the attaching face of the lift but it is apparent that the tread face 50 thereof would, for the sake of having a heel of uniform thickness throughout in order to have a perfectly flat tread face when attached, correspond to a section of a parallel cone.

55 In addition to the advantages above pointed out, it will be evident to those familiar with the practical art, that the plungers of the moulds for the manufacture of my improved heel lift may be produced by a simple milling process, and therefore, do not require any special form of dies, such as are commonly used in making moulds for lifts of the double curved concavo-convex type, as heretofore produced in the art. The milling 60 process is more accurate than the die stamp-

ing process, and therefore, results in a more uniform and accurately constructed lift.

It is to be particularly noted that, while the embodiment illustrated and described herein is a heel having its attaching face 70 edge lying in a plane, the scope of my invention should not be limited to a lift so constructed, for a nonplane attaching face edge can readily be embodied in a heel of this type and as a matter of fact such an 75 edge would likely result from assuming conditions other than those above assumed for the directrices of the conical surface. For example, assuming that the curvature of the breast edge 17 extending between the corners 10—12 is first determined, the generatrix may move along this breast edge from one breast corner to the other, always passing through the point 15 to produce a conical surface of indefinite area. The shape of 80 a standard shoe heel is then laid out on this conical surface extending from the breast corner 10 through the rear end 11 to the other breast corner 12 and the lift then cut from the material in accordance therewith. 85 In this case, the attaching face edge would not lie in a single plane, it being understood of course that the curvature of the breast edge 17 is other than that illustrated in the drawing. In this suggested modification, 90 only the opposite breast corners 10—12 and the rear central point 11 of the attaching face edge would lie in the same plane.

Having thus described one practical and satisfactory embodiment of my invention 100 it is nevertheless to be understood that the same is susceptible of many modifications, and I accordingly reserve the privilege of adopting all such changes as may be fairly embodied within the spirit and scope of the 105 invention claimed.

What I claim is:

1. A resilient heel lift of the concavo-convex type having a concave attaching face, every transverse cross-sectional element of 110 which in planes perpendicular to the marginal edge of the lift is a continuous unbroken arc, said arcs progressively increasing in radii from the breast edge to the rear end of the lift and all parts of said concave 115 attaching face being completely developable into a plane surface.

2. A resilient heel lift of the concavo-convex type having an attaching face completely developable into a plane surface, said attaching face along its central longitudinal dimension extending in a straight line, and presenting arcs in all planes perpendicular to the longitudinal center line of the lift, 120 said arcs being of gradually decreasing curvature from the breast edge to the rear end of the lift.

3. A resilient heel lift of the concavo-convex type having an attaching face completely developable into a plane surface, every 130

rectilinear element of said attaching face extending in a straight line between the breast edge and the attaching face edge of the lift converging to a common point located in spaced relation to the breast edge of the lift.

4. A resilient heel lift having an attaching face all parts of which lie below a plane coinciding with the rear end of the attaching face edge and the breast corners, said attaching face corresponding in geometrical form with a section of a conical surface.

5. A resilient heel lift having an attaching face presenting transverse circular arcs of progressively decreasing depths from the breast edge to the rear end of the lift, and said arcs corresponding in curvature to

the consecutive circumferential elements of the same conical surface.

6. A resilient heel lift of the concavo-convex type having an attaching face corresponding in geometrical form with a section of a conical surface and having a tread face corresponding in geometrical form with a section of a conical surface, said lift being of uniform thickness throughout its area and said attaching and tread surfaces presenting transverse arcs of progressively decreasing depth from the breast edge to the rear end of the lift.

In testimony that I claim the foregoing as my invention I have signed my name hereunder.

JOHN W. AYMAR, JR.
